Specification for Design.

Patented Aug. 10, 1920.

Application filed April 12, 1920. Serial No. 373,395. Term of patent 14 years.

To all whom it may concern:

Be it known that I, JAMES H. SMITH, a citizen of the United States, residing at Rochester, in the county of Monroe and State of New York, have invented a new, original, and ornamental Design for a Duplex Container, of which the following is a specification, reference being had to the accompanying drawing, forming part thereof.

Figure 1 is a plan view of a container showing my new design; and
Fig. 2 is an end view thereof.

I claim:

The ornamental design for a duplex container, as shown.

JAMES H. SMITH.
